UNITED STATES PATENT OFFICE

2,340,301

ADJUSTABLE LINK AND CLAMP ASSEMBLY

James H. Booth, Detroit, Mich., assignor to
Thompson Products, Incorporated, Cleveland,
Ohio, a corporation of Ohio

Application March 24, 1943, Serial No. 480,327

13 Claims. (Cl. 287—117)

This invention relates to adjustable linkages wherein telescoped members are adjusted longitudinally by means of a single enveloping member.

Specifically, the invention relates to an adjustable tie rod and tie rod end assembly including a contractible clamp having two sets of threads respectively engaging the tie rod and tie rod end.

While the invention will be specifically herein-after described as embodied in a tie rod and tie rod end assembly, it should be understood that the invention is not limited to such an embodiment since it is generally concerned with adjustable linkages.

According to this invention a hollow tie rod has diametrically opposed slots extending inwardly from one end thereof and is externally threaded inwardly from this same end. A tie rod end has a stem or shank extending into the tie rod and equipped with longitudinal keys which project into the tie rod slots to terminate at levels beneath the root diameter of the threads on the tie rod. Each of these keys has spaced lugs sloping transversely thereacross at the same pitch angle and projecting above the tie rod. These lugs are arranged to serve as screw threads. A split clamp is threaded onto the tie rod and has spirally arranged keyways receiving the lugs on the stem. The keyways and lugs cooperate to form a coarse threaded connection extending in the same direction as the threads on the tie rod. As the clamp is rotated on the tie rod, it moves toward or away from the free end of the rod by virtue of the threaded connection therewith. At the same time, however, the lug and keyway connection between the clamp and the tie rod end effects longitudinal shifting of the tie rod end into or out of the rod. The engaging threads of the tie rod and clamp are much finer and have a lesser pitch than the thread connections formed by the lugs and keyways so that, when the clamp is rotated one turn on the tie rod, it will only advance a small distance on the tie rod but this one turn will effect an appreciable movement of the tie rod end into or out of the tie rod. The adjustment of the tie rod end is effected by the differences in lead or pitch of the two sets of threads since both sets of threads extend in the same direction.

Thus if the threads connecting the clamp with the tie rod have a $\frac{1}{8}$ inch lead per revolution, and the threads connecting the clamp with the tie rod end have a $\frac{1}{2}$ inch lead per revolution, one revolution of the clamp in one direction on the tie rod will move the tie rod end in the opposite direction an amount equal to the difference

between the leads of the two sets of threads, or $\frac{1}{8}$ of an inch.

It is, then, an object of this invention to provide an adjustable link assembly wherein male and female members are moved toward and away from each other by means of a single member on the female member having threads of one lead engaging the female member and threads of another lead engaging the male member.

10 A further object of the invention is to provide an adjustable link assembly wherein telescoped members are adjusted through right or left-hand pairs of threads having different leads.

15 A still further object of the invention is to provide a tie rod and tie rod end assembly wherein the tie rod end is adjusted into and out of the tie rod by an internally threaded member having one set of threads engaging the tie rod and another set of threads extending in the same direction but having a different lead engaging the tie rod end.

20 A still further object of the invention is to provide a tie rod and tie rod end assembly wherein the tie rod end is adjusted relative to the tie rod by means of a clamp having a coarse thread 25 for engaging one of the members and a fine thread for engaging the other member.

Another object of the invention is to provide a tie rod and tie rod end assembly wherein the tie rod is slotted and receives the stem of a tie rod end and wherein the tie rod end stem has lugs thereon engageable in keyways of a clamp threaded onto the tie rod.

30 Other and further objects of the invention will 35 be apparent to those skilled in the art from the following detailed description of the annexed sheet of drawings which, by way of preferred example, illustrate one embodiment of the invention.

40 On the drawing:

Figure 1 is a fragmentary side elevational view of a tie rod and tie rod end assembly according to this invention.

45 Figure 2 is a somewhat enlarged plan view with parts broken away and shown in horizontal cross section of the assembly of Figure 1.

Figure 3 is a view similar to Figure 2 illustrating the positions of the parts after the clamp has been rotated one turn.

50 Figure 4 is a vertical cross-sectional view, with parts in elevation, taken generally along the line IV—IV of Figure 1.

55 Figure 5 is a longitudinal cross-sectional view of the clamp shown in Figures 1 to 4 prior to the cutting of the fine threads therein.

Figure 6 is a view similar to Figure 5 illustrating the clamp after the fine threads have been cut therein.

As shown on the drawing:

In Figures 1 to 4, the reference numeral 10 designates a hollow tubular tie rod with an externally threaded end portion 11 having diametrically opposed slots 12-12 extending inwardly from the threaded end thereof.

A tie rod end 13 has a socket 14 tiltably and rotatably supporting a stud 15. A shank or stem 16 projects laterally from the socket 14 into the tie rod 10. This shank 16 has longitudinally extending keys 17-17 extending into the slots 12-12 but terminating at levels beneath the root diameter of the threads on the threaded end 11 of the rod. Each key 17-17 has a plurality of upstanding lugs 18 at spaced intervals along the length thereof extending in a sloping direction across the widths of the keys. These lugs 18 are helically arranged.

A clamp 19 has a ridged sleeve portion 20 enveloping the threaded end 11 of the tie rod 10 together with spaced opposed apertured ears 21-21 depending therefrom. These ears receive, as shown in Figure 4, a bolt 22 therethrough. A nut 23 threaded on the bolt serves to draw the ears 21-21 together for clamping the sleeve portion 20 on the tie rod.

As shown in Figure 5, the sleeve portion 20 of the clamp 19 has ridges therein defining keyways 24 around the inside of the sleeve. These keyways are arranged in a helical path to receive the lugs 18 of the tie rod end. Cylindrical land areas 25 are provided between each keyway 24. These land areas 25, as shown in Figure 6, are threaded as at 26 with a thread adapted to receive the thread on the end 11 of the tie rod 10.

The clamp 19 can be made from a flat sheet of metal by stamping the ridges therein to form the keyways 24. In the flat condition these ridges will extend lengthwise of the sheet in parallel relation at an angle coinciding with the desired helix angle. When the blank is still in the flat stage of fabrication, the ears 21-21 can be formed therein. The thus-shaped blank is wrapped to a circular inside diameter to form the sleeve portion 20. A machine-cut thread is then tapped into the minor diameter of the circular sleeve portion 20 to form the threads 26 on the land areas 25. The keyways 24 and the threads 26 extend in the same direction and can be considered as threads of the same hand. When using $\frac{1}{8}$ inch metal stock to form the clamp, for example, the stamped in threads or keyways 24 preferably have a lead around $\frac{1}{2}$ inch per revolution and the stock is bent to a 1 inch minor diameter. The small threads 26 in such installations then preferably have a $\frac{1}{16}$ or $\frac{1}{8}$ inch lead per revolution.

As illustrated in Figures 2 and 3, when the clamp 19 is rotated on the threaded end 11 of the rod 10 for one revolution to move the clamp away from flush relation with the free end of the rod as shown in Figure 2, to the position shown in Figure 3, the cooperating lugs 18 on the tie rod end shank 16 and the keyways 24 will move the shank 16 out of the rod 10 a distance equivalent to the difference in lead of the two sets of threads. Thus if the clamp 19 advances $\frac{1}{16}$ inch on the rod 10, the shank 16 will move out of the rod a much greater distance depending upon the difference in lead of the lugs 18 and keyways 24 and the threads 26 and threads on the end 11. If the keyways and lugs have a $\frac{1}{2}$ inch lead, and

the end 11 and threads 26 have a $\frac{1}{16}$ inch lead, the tie rod end will move out of the tie rod a distance of $\frac{7}{16}$ inch per revolution of the clamp.

The slots 12-12 in their free state are wider than the keys 17-17 so that the clamp 19 can contract the rod tightly around the shank or stem 16 of the tie rod end, to lock the members in adjusted position.

Alternately the tie rod 10 could have lugs projecting into keyways 24 of a clamp and the tie rod end could have machine cut threads on the keys 17-17 thereof engaging similarly cut threads in the clamp.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. An adjustable link assembly comprising a female member having an external threaded portion and a longitudinal slot therethrough along said threaded portion, a male member in said female member having a lug projecting through said slot, and a sleeve threaded on said female member having a helical keyway of different pitch than the pitch of the thread on the female member receiving said lug whereby rotation of the sleeve on the female member will longitudinally shift the male member in the female member.

2. An adjustable link assembly comprising longitudinally shiftable telescoped members, the outer member of said telescoped members being externally threaded and having a longitudinal slot therethrough, threads on the inner of said telescoped members projecting through said slot, a sleeve threaded on the outer member having a second thread engaging the projecting threads of said inner member and said sets of cooperating threads having different leads extending in the same direction.

3. An adjustable link assembly comprising longitudinally shiftable links each having external threads extending in the same direction, said threads having different leads, and an internally threaded sleeve member enveloping said members having sets of threads engaging the threads of the members whereby rotation of said sleeve will longitudinally shift the members in accordance with the differences in leads of said threads.

4. A rod and tube assembly comprising a hollow externally threaded tube having a longitudinal slot along the threaded portion thereof, a rod inserted in said tube having spaced thread-providing lugs projecting through said slot above the root diameter of the threads on the tube, and a sleeve threaded on said tube having thread-forming keyways receiving said lugs, said lugs and keyways having a different lead than the thread on the tube whereby rotation of the sleeve on the tube will longitudinally shift the rod in accordance with the difference in leads of the threads.

5. A tie rod and tie rod end assembly comprising a tie rod having a hollow end portion with an external thread therearound, said tie rod having a longitudinal slot extending inwardly from the end thereof, a tie rod end having a stem seated in said tie rod, said stem having a transversely extending lug projecting through the slot of the rod above the root diameter of the threads on the rod, and a clamp threaded on said rod

having a helical keyway receiving said lug, said clamp being contractible to clamp the rod onto said stem.

6. A tie rod and tie rod end assembly comprising a tie rod having a hollow longitudinally slotted externally threaded end portion, a tie rod end having a stem seated in said end portion, an inclined transverse lug on said stem projecting through said slot above the root diameter of the thread on the rod, and a clamp threaded on said rod having a helical keyway receiving said lug.

7. A tie rod and tie rod end assembly comprising a tubular tie rod having an externally threaded end portion with diametrically opposed slots extending longitudinally inward from the end of the rod, a tie rod end having a stem seated in said tie rod, said tie rod end having longitudinally extending keys thereon projecting into said slot and terminating at a level beneath the root diameter of the thread on the rod, each of said keys having spaced transverse lugs projecting therefrom above the root diameter of the thread on the rod, a clamp threaded on said rod having a helical keyway receiving said lugs, and means for contracting said clamp to secure the stem in the tie rod.

8. A tie rod and tie rod end assembly comprising a hollow tubular rod having an external fine thread therearound and a longitudinal slot therethrough along the threaded portion thereof, a tie rod end having a stem seated in said tie rod, means on said stem projecting through said slot, and a sleeve threaded on said tie rod having a coarse keyway receiving said means.

9. A clamp assembly comprising a split member having a sleeve portion and spaced opposed depending clamping ears, said sleeve portion having ridges providing a helical keyway therein, and

threads in said sleeve portion between the helical keyway.

10. A tie rod end socket having a laterally extending stem, a raised longitudinally extending key on said stem, and lugs on said key projecting in spaced relation from each other above the key.

11. An adjustable link assembly comprising a slotted female member, a male member extending into the female member, a sleeve on the female member, means rotatably connecting the sleeve and female member, and means acting through the slot of the female member connecting the sleeve and male member to cooperate with said means rotatably connecting the sleeve and female member for effecting relative shifting of the male and female members upon rotation of the sleeve.

12. An adjustable link assembly comprising a slotted female member, a male member extending into said female member having a key projecting into the slot of the female member, and a sleeve member having separate sets of different threads respectively engaging the female member and the key arranged to longitudinally shift the male and female members upon rotation of the sleeve.

13. A tie rod and tie rod end assembly comprising a hollow tie rod having a longitudinal slot therein, a tie rod end having a stem projecting into said tie rod, a key on said stem cooperating with said slot in the tie rod to hold the tie rod end against substantial rotation relative to the tie rod, and a sleeve rotatable on said tie rod having separate sets of different threads respectively cooperating with the tie rod and tie rod end to shift the tie rod end relative to the tie rod upon rotation of the sleeve.

JAMES H. BOOTH.
